CLAIM

The ornamental design for a decorative painted woven mat, as shown and described.

DESCRIPTION

FIG. 1 is a front perspective view of a novel decorative painted woven mat including a painted lighthouse constructed in accordance with the present invention;

FIG. 2 is a top plan view of the novel decorative painted woven mat of FIG. 1;

FIG. 3 is a bottom plan view of the novel decorative painted woven mat of FIG. 1;

FIG. 4 is a right side elevational view of the novel decorative painted woven mat of FIG. 1;

FIG. 5 is a left side elevational view of the novel decorative painted woven mat of FIG. 1;

FIG. 6 is a front side elevational view of the novel decorative painted woven mat of FIG. 1 the back side being a mirror image of the front side; and,

FIG. 7 is a cross-sectional of the novel decorative painted woven mat taken across the painted lighthouse of FIG. 1 illustrating the cohesion between the paint and rope substrate.
